(57) **CLAIM**

The ornamental design for an arm rest for manicure as shown and described.

DESCRIPTION

1. Arm rest for manicure

1.1 : Perspective

1.2 : Front

1.3 : Back

1.4 : Left

1.5 : Right

1.6 : Top

1.7 : Bottom

1.8 : Perspective

Fig. 1.1 is a front, right side, top perspective view of an arm rest for manicure showing the claimed design; Fig. 1.2 is a front elevational view thereof; Fig. 1.3 is a rear elevational view thereof; Fig. 1.4 is a left side elevational view thereof; Fig. 1.5 is a right side elevational view thereof; Fig. 1.6 is a top plan view thereof; Fig. 1.7 is a bottom plan view thereof; and Fig. 1.8 is a rear, left side, bottom perspective view thereof.

1 Claim, 8 Drawing Sheets
